CLAIM

The ornamental design for a fiber optic cable bend radius limiter, as shown and described.

DESCRIPTION

FIG. 1 is a perspective view of a fiber optic cable bend radius limiter of the present invention.

FIG. 2 is a top view thereof.

FIG. 3 is a front view thereof.

FIG. 4 is a side view thereof, from the right side of FIG. 3.

FIG. 5 is a side view thereof, from the left side of FIG. 3.

FIG. 6 is a rear view thereof; and,

FIG. 7 is a bottom view thereof.
